UNITED STATES PATENT OFFICE

NORWOOD H. KNOWLTON, OF ROCKPORT, MASSACHUSETTS, ASSIGNOR TO UNITED SHOE MACHINERY CORPORATION, OF PATERSON, NEW JERSEY, A CORPORATION OF NEW JERSEY

MACHINE FOR LAYING BREAST COVERS ON HEELS

Application filed December 4, 1928. Serial No. 323,753.

This invention relates to machines for laying breast covers on heels, and has for an object the provision for this work of a machine which shall be extremely simple in structure and smooth in action and yet shall be more efficient and produce better results than any of the machines heretofore available for this operation.

High heels for women's shoes are usually made of wood, the breast, sides and rear of such heels being covered with a thin layer of leather or other suitable material to give a finished appearance to the heel and make it harmonize with the rest of the shoe. The function of the machine illustrated herein is to lay and beat the covering material into intimate contact with the breast face of a heel, so that the cover shall be smooth and adhere firmly to the heel breast.

The present invention provides a machine which is useful in operating both upon heels of which the breast is covered with a separate piece of material and those of which the breast is covered with a flap split from the outer portion of the heel end of the shoe sole and remaining attached to the sole, the last-mentioned arrangement being the most common in the case of Louis heels.

Heel breast covers are often buffed prior to the laying operation producing a delicate, velvety surface, free from gloss, the perfection of which is marred by the rotary metal tools generally employed in breast cover laying, such tools having a rubbing, ironing action which lays the nap on the buffed surface and often produces spots having a more or less polished appearance upon said surface. The rubbing action of the rotary tool may also cause dragging or displacement of the cover with resultant wrinkling, or poor adhesion to the heel breast. On the other hand, the known beating machines of the percussion type, in which the tool has a rapid reciprocating movement, are not adapted to operate in the restricted space between the heel breast and the shank of the shoe sole and, furthermore, these machines create a great deal of noise and vibration, with consequent unnecessary fatigue to the operator.

These drawbacks are overcome by the pres-

ent invention, an important feature of which consists in a cover laying tool mounted upon a non-rotatable carrier, herein shown as a pin, which is movable in a closed path. The work engaging member, or tool, is preferably a sleeve which is freely rotatable upon the pin. By employing a non-rotating tool carrier and making the tool freely rotatable upon it the tendency of the tool to rub or iron the surface of the work is practically eliminated, though the tool moves continuously in a closed path, permitting quiet and comparatively vibrationless operation of the machine.

In order further to reduce the danger of the work engaging sleeve, or laying tool, marring delicate surfaces it preferably consists of a roll of soft material, such as rubber, and invention is to be recognized in such a laying tool mounted for free rotary movement upon a pin which is bodily movable in a closed path, whether the pin itself is rotatable or not.

In order effectively to operate in the restricted space in front of the heel breast which is to be covered, the cover laying roll in the illustrated machine is made of small diameter and is moved bodily in a closed path of only slightly greater diameter than that of the roll itself, its carrier being supported upon a rotatable crank pin and being prevented from rotation by a stationary abutment co-operating with an arm extending radially from the carrier.

These and other features and advantages of the invention will be better understood and appreciated from reading the following detailed description of one embodiment thereof in connection with the accompanying drawings, in which

Fig. 1 is a view of the machine in front elevation and longitudinal section;

Fig. 2 is a perspective view of the essential parts of the machine; and

Fig. 3 is a fragmentary view showing the relation of the laying roll to the work.

In the machine illustrated in the drawings, 10 indicates any suitable base or support for a pair of aligned bearings 12 adapted to re-

ceive a main driving shaft 14 upon which is a pulley 16, driven by a belt 18.

Upon the end of the shaft 14, which is driven continuously, is a crank pin 20 which is offset only slightly from the axis of the shaft so that it has a very short throw, in the actual machine only about a sixteenth of an inch. The crank pin 20, as well as the shaft 14, of which it is virtually or actually a part, is provided with an axial oil passage 22 and radial holes 24 permit lubricating oil to pass out to the surface of the crank pin.

Supported upon the crank pin 20 is a tool carrier 26 which fits the crank pin snugly but within which the crank pin is freely rotatable. The tool carrier is provided with a rigid extension spindle or pin 28 the axis of which coincides with the axis of the hole in the carrier 26 in which the crank pin has its bearing. Journaled upon the pin 28 is a work engaging sleeve or laying tool 30 which is preferably made of fairly soft material and is herein shown as consisting of a rubber roll secured to a metal sleeve 32 fitting closely upon the pin 28 but freely rotatable thereon.

In order to overcome the tendency of the tool carrier 26 to rotate with the crank pin 20, and positively to prevent rotation of the tool carrier, the carrier is provided with a radial arm 34, the lower end of which is bifurcated and embraces an abutment consisting of a block 36 arranged to rock freely upon a pivot pin 38 which is secured in a stationary housing 40 by a screw 42. The housing 40 is formed, as shown, to provide an oil reservoir in which the bifurcated end of the arm 34 has sliding contact with the block 36.

By virtue of the described construction the roll 30, when the machine is running idle, has no definite tendency to rotate since the spindle or pin 28 does not rotate, although it is moved continuously by the circularly rotating crank pin 20. Inasmuch as the pin 28 is coaxial with the crank pin 20 any point in the axis of the pin 28 moves in a small circle. All other points in the tool carrier 26 and all points in the surface of the tool 30 move in closed paths which are not circles, being modified by the restraining action of the arm 34, but are sufficiently convex to provide very smooth, relatively vibrationless, operation as compared with machines embodying reciprocating operating elements. It will be understood that points in the surface of the tool 30 all move continuously in the same direction in closed paths of only slightly greater diameter than that of the tool itself and, inasmuch as the tool is freely movable upon the spindle 28 and is not rotating when it engages the work, there is no substantial tendency for the working surface of the tool to rub or iron the surface of the work which it engages. Furthermore, since the work engaging portion of the tool is made of soft or

yielding material there is substantially no tendency to mar delicate materials being operated upon.

In Figs. 2 and 3 of the drawings the machine is shown in the operation of laying a flap 44 upon the breast face of a heel 46 which has previously been secured to a shoe 48. The covering for the heel breast may be a continuation of the sole 50 of the shoe, as illustrated, or may be a separate piece of material, it being understood that a coating of adhesive has previously been applied and that the function of the machine is to lay and beat the covering material into intimate contact with the breast face of the heel so that the cover shall be smooth and shall adhere firmly to the heel breast.

In operation, with the machine running continuously, the work is manipulated in engagement with the cover laying roll 30 until the cover is laid smoothly and securely in position. This may be done very rapidly and perfectly with a minimum of effort by the operator.

Having described the invention, what is claimed as new and desired to be secured by Letters Patent is:

1. In a machine for laying breast covers on heels, a laying tool carrier movable in a closed path, means for preventing rotation of said carrier, and a cover laying tool mounted upon said carrier.

2. A machine for laying breast covers on heels, comprising a non-rotatable pin bodily movable in a closed path, and a freely rotatable work engaging sleeve upon the pin.

3. A machine for laying breast covers on heels, comprising a pin bodily movable in a closed path, and a freely rotatable sleeve of soft material upon the pin.

4. A machine for laying breast covers on heels, comprising a non-rotatable pin bodily movable in a closed path, and a freely rotatable sleeve of soft material upon the pin.

5. A machine for laying breast covers on heels, comprising a non-rotatable pin bodily movable in a closed path, and a freely rotatable soft rubber laying tool upon the pin.

6. In a machine for laying breast covers on heels, a freely rotatable cover laying roll of small diameter and means for moving said roll bodily in a closed path of only slightly greater diameter than that of the roll.

7. A machine for laying breast covers on heels, comprising a non-rotatable pin the axis of which is movable bodily in a circle about an axis parallel to itself, and a cover laying tool consisting of a sleeve of yielding material loosely mounted upon said pin.

8. A machine for laying breast covers on heels, comprising a rotatable shaft, a crank pin secured to said shaft parallel to the axis thereof, a cover laying tool carrier engaged by said crank pin, and a cover laying tool loosely mounted upon said carrier.

9. A machine for laying breast covers on heels, comprising a rotatable crank pin, a cover laying tool carrier supported upon said crank pin, an arm rigid with the carrier and extending radially therefrom, a stationary abutment cooperating with said arm to prevent rotary movement thereof, a tool receiving pin rigid with the carrier, and a cover laying tool loosely mounted upon said tool receiving pin.

In testimony whereof I have signed my name to this specification.
